CLAIM

We claim The ornamental design for a workstation, as shown and described.

DESCRIPTION

FIG. 1 is a top front right perspective view of our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a rear perspective view thereof.

The views of the workstation not shown form no part of the claimed design. The dash-dot lines in the figures show features that form no part of the claimed design. The dash-dot lines represent unclaimed boundaries of the claimed design.
